APPARATUS FOR BLOWING WELLS

Granville A. Humason, Houston, Tex.

Application August 28, 1933, Serial No. 687,140

5 Claims. (Cl. 103—233)

My invention relates to control valves to be employed in blowing wells with air or gas to raise the liquid therefrom.

In order to employ the air or gas to raise the liquid already standing in the well, it is now common to employ control valves arranged at different levels along the tube to admit the pressure fluid first at an upper stage and then at successively lower stages until the air or gas may enter the lower end of the tubing and continually blow the well from the lower end of the tube. By so doing, it is possible with a comparatively low air or gas pressure to raise the liquid from the well.

15 It is an object of my invention to provide a control valve for the purpose stated which will operate accurately to remain open until the liquid level has passed below the level of the valve and to then close so that no more of the pressure 20 fluid may enter at that level.

It is a further object to provide means whereby the liquid above the opening in the eduction tube may be prevented from flowing backwardly toward the lower end of the well and to thus 25 take the pressure of the head of liquid off the lower end of the well.

It is a further object to provide a particular construction of lower valve through which the air may continuously blow after the head of 30 liquid in the tube has been started in its flow from the well.

In the drawing herewith Fig. 1 is a central, longitudinal section through a well casing showing therein a valve embodying my invention.

35 Fig. 2 is a transverse section on the plane 2—2 of Fig. 1.

In the drawing, the well casing is shown at 1. The well tubing 2 therein has at intervals along 40 its length, a series of housings 3 connected in the tubing and having therein a control valve for regulating the admission of air to the tubing at that level.

In the drawing, the housing 3 is connected at its upper end to the tube 2, and at its lower 45 end is connected with a lower section of tubing 2'.

The interior of the housing 3 is divided by a partition 4 into an upper chamber 5 and a lower valve chamber 6.

50 The lower valve chamber is annular in shape and has a central mandrel 7 extending therethrough. Said mandrel has a central passage 8 extending longitudinally thereof, and projects above the partition 4 into which it fits closely. Its upper end projects into the chamber 5 and 55 has thereon a valve housing 9 which serves to

secure a valve seat 10 in position at the upper end of the mandrel and provides a seat for the ball valve 11. The lower end of the post or mandrel 7 is threaded for engagement within the lower block 12 of the housing.

In the chamber 6 there is a ring valve 13 which fits within an annular tapered seat 14 in said chamber. Said valve serves to close the upper outlet from passages 15 through which the pressure fluid may enter into the passage 8 through the mandrel. There are a plurality of such passages 15 adapted to be controlled by the ring valve 13. Said valve has a float member 16 thereon which extends upwardly to a point spaced slightly below the partition 4 and acts when the valve is submerged to hold the valve upwardly spaced away from its seat.

The lateral walls of the chamber 6 are perforated with openings 17 which allow entrance of fluid to the said chamber.

The block 12 which closes the lower end of the housing 3 has below the chamber 6 a partition 18 into which the mandrel is threaded as previously noted. Below this partition is a valve chamber 19 in the lower end of which is a seat 20 for a ball valve 21 which prevents the backward passage of fluid into the well.

As will be noted in the drawing, there are passages indicated by dotted lines at 22 in Fig. 1 and at the center portion of Fig. 2 extending longitudinally of the mandrel from the valve chamber 19 upwardly into the chamber 5 where they discharge laterally at 23 into said chamber. These passages allow fluid from the well to be conducted upwardly past the control valve 90 into the tubing above.

When this device is used in the well, the tubing will be positioned with the control valve submerged below the level of the liquid in the well. If air or gas pressure is exerted upon the liquid in the well and between the casing and the tubing, it will tend to force the liquid through the opening 17 and past the valve 13 which will be raised due to its submergence in the liquid. The liquid will then pass into the central passage 8 and past the valve 11 upwardly into the tubing. As the liquid level is depressed, gas will finally enter before the closing of the valve and aerate the column of liquid above. As the level of liquid reaches a point approximately adjacent the lower end of the float the valve will gradually be lowered into its seat and eventually cut off the flow of fluid into the tubing. The continued pressure of the gas in the casing will depress the head of liquid 110

and force said liquid through the next lower valve. At the extreme lower end of the tubing, the float may be omitted and I have shown at 24 a valve housing for positioning such lower 5 end of the eduction tube. This housing has therein a valve chamber 25, the lower end of which is closed by the head 26. Passages indicated at 27 in dotted lines extend longitudinally through the head for connection with the 10 valve chamber 28 at the lower end thereof. Centrally of the head is a passage 29 longitudinally of the head, which connects at its lower end with lateral passages 30 extending to the outside and connecting with the space between the 15 tube and the housing.

At the upper end of the passage 29 is a valve seat 31 adapted to be closed by a ball valve 32 whose upward movement is limited by a transverse pin 33.

20 The valve chamber 28 has a valve seat 34 at its lower end upon which is seated the ball valve 35. At the lower end of the head 26 is connected a nipple 36 which is in turn connected to the upper end 37 of an inlet pipe or screen through 25 which the liquid may enter the tubing.

It will be obvious that when the liquid level 30 has been depressed to the point indicated by the passage 30, the air will blow in through the passage 29 and serve continuously to raise the liquid upwardly in the tube. The liquid will enter through the valve chamber 28 and the passages 27 through the housing and around the valve chamber housing the valve 32. The air flowing upwardly through the central passage will have 35 an injector effect to cause a continuous flow of air or gas and liquid upwardly in the tubing.

It is to be understood that the control valves such as are employed along the length of the tubing will only be of use in starting the well to 40 flow, and will avoid the use of a heavy pressure upon the gaseous fluid to start the well operating. In cases where the well is idle at frequent intervals valves of this character are a practical necessity and the particular structure of valve 45 disclosed herein has various advantages which have been previously noted.

This valve will operate accurately to stay open until the level of liquid has been depressed below 50 the valve and will then close and prevent the entrance of further pressure fluid at that level. It is an accurate and reliable control improvement and will not tend to get out of order or wear in use.

Having described my invention, what I claim is: 55

1. An apparatus for blowing wells comprising a well tubing, blowing attachments arranged at intervals along said tubing, comprising coupling in said tubing, each coupling allowing a passage of fluid therethrough and forming a housing, upper

and lower chambers therein, said lower chamber being perforated, a longitudinal tube connecting said chambers, a valve closing the upper end of said tube, a float valve adapted, when not submerged, to close connection between said lower chamber and said tube, and separate channels in the walls of said tube connecting the tubing below said housing with said upper chamber. 8

2. An apparatus for blowing wells comprising a well tubing, blowing attachments arranged at different levels along said tubing, each attachment comprising couplings in said tubing, each coupling allowing a passage of fluid therethrough and forming a housing, upper and lower chambers therein, said lower chamber having openings to the outside, a central tube connecting said chambers, a valve at the upper end of said tube, means adapted when not submerged to close the connection between said lower chamber and said tube and means allowing passage of fluid from below said housing to said upper chamber. 9

3. An apparatus for blowing wells comprising a well tubing, blowing attachments arranged at different levels along said tubing, each attachment comprising couplings in said tubing, each coupling allowing a passage of fluid therethrough and forming a housing, upper and lower chambers therein, said lower chamber having openings to the outside, a tube connecting said chambers, means to prevent movement of fluid in said tube, 10 means adapted to close the connection between said chambers when said chambers are not submerged, and separate channels connecting the tubing below said housing with said upper chamber. 10

4. An apparatus for blowing wells, comprising a well tubing, blowing attachments comprising tubular couplings arranged at intervals along said tubing and forming a passage for fluid, said attachments above the bottom of the well comprising automatically closing inlets for fluid under pressure to said tubing, said attachments at the bottom of the well comprising an opening from outside said tubing through the interior thereof, and a valve preventing the flow of fluid outwardly from said passage in the manner described. 115

5. An apparatus for blowing wells comprising a tubing, a blower attachment spaced below the upper end of said tubing having a valve closed 125 passage therethrough, said attachment forming a part of said tubing, means for closing the outlet of liquid from below said passage, means to force fluid from without the tubing in through said blower and up through said tubing and float operated means to close the inlet of fluid into said attachment. 130
